UNITED STATES PATENT OFFICE.

FREDERICK K. LANDGRAF, OF PITTSBURGH, PENNSYLVANIA, ASSIGNOR TO FLAN-
NERY BOLT COMPANY, OF PITTSBURGH, PENNSYLVANIA, A CORPORATION OF
DELAWARE.

STAY-BOLT STRUCTURE.

Application filed January 11, 1921. Serial No. 436,473.

To all whom it may concern:

Be it known that I, FREDERICK K. LANDGRAF, a citizen of the United States, and a resident of Pittsburgh, in the county of 5 Allegheny and State of Pennsylvania, have invented certain new and useful Improvements in Stay-Bolt Structures; and I do hereby declare the following to be a full, clear, and exact description of the invention, 10 such as will enable others skilled in the art to which it appertains to make and use the same.

This invention relates to improvements in staybolt structures for boilers.

15 In types of "flexible" staybolt structures in which caps are provided to enclose the bearing of the headed end of the staybolt, it is necessary in many instances to remove such caps periodically for inspection purposes. The caps have usually been threaded to sleeves in which the bolt heads have their bearings, and it has been found that when the threaded caps shall have been replaced, it is difficult to effect a steam tight joint. 20 To provide loose fitting gaskets is not satisfactory, first because they do not sufficiently cover the shoulders in the sleeves which provide abutments for the caps, and second because they are liable to be lost when the 25 caps are removed.

30 One object of my present invention is to provide, in a staybolt structure, a gasket disposed between the cap and its abutment in the sleeve in such manner that it shall sufficiently cover the abutment in one part 35 for the other part, to insure a steam tight joint and prevent leakage past the threaded connection between said parts and so that the gasket will be held against accidental 40 loss when a cap is removed.

With these and other objects in view, the invention consists in certain novel features of construction and combinations of parts as hereinafter set forth and pointed out in 45 the claims.

50 In the accompanying drawings; Figure 1 is a sectional view of a staybolt structure showing an embodiment of my invention, and Figures 2 and 3 are views illustrating the manner in which the gasket may be applied.

55 1 and 2 represent, respectively, an inner and an outer boiler sheet, the latter being shown as being provided with an opening having a threaded wall 3 to receive the externally

threaded wall of a bearing sleeve 4. The bearing sleeve 4 is provided interiorly with a rounded seat 5 for the rounded head 6 at the outer end of a staybolt 7, whereby a flexible connection is effected for the stay- 60 bolt with the outer boiler sheet. The inner end of the staybolt may be secured in any suitable manner to the inner boiler sheet, as by threading the bolt through said sheet as at 8 and upsetting its inner end, as at 9. 65

The bearing sleeve 4 projects outwardly beyond the outer boiler sheet and its threaded exterior receives the interiorly threaded portion 10 of a cap 11 which acts as a closure for the bearing sleeve, over 70 the bolt head.

It is important that the connection of the cap or closure 11 with the bearing sleeve shall be kept steam-tight at all times and to insure this, I employ a gasket 12 which is so 75 applied that it shall so completely cover the abutment in one of said parts for the other part that it shall extend radially beyond the free edges of the screw-threads.

In the embodiment of the invention shown 80 in the drawing, the cap or closure 11 is formed interiorly inwardly, beyond the threaded portion, with a shoulder or abutment 13 which may be slightly inclined and extends radially beyond the free edge of 85

the threads. The gasket, 12, which may be made of copper or a copper alloy, is initially so shaped that it may readily pass the threads when inserted into the cap and caused to rest on the shoulder or abutment 90

13. In the construction shown in the drawing, the gasket is annular and is initially made somewhat tapering or the shape of a cross-sectional portion of a hollow cone as shown at 14. In applying the gasket, the 95

cap or closure 11 may be mounted on a support 15 having a depression of suitable shape and size to receive the dome portion of the cap when the latter is inverted as shown in Figures 2 and 3. In the drawing, 100 I have shown depressions 16 and 17 in the support to accommodate caps of different dimensions. A cap 11 having been mounted on the support 15 in inverted position, the tapering gasket 14 will be dropped into 105 it and permitted to rest upon the shoulder or abutment 13 as shown in Figure 2. The

head 18 of a tool 19 will then be inserted into the cap, said head having an annular shoulder 20 and a tapering portion 21. By 110

now applying pressure, with the use of a hammer or otherwise, to the tool, the tapering or conical gasket 14 will be expanded and flattened so that it will be caused to lie flat against the shoulder or abutment 13 and to extend radially beyond the free edge of the screw threads, thus forming the gasket 12. The gasket will not only be prevented by the threaded portion of the cap 10 from escaping, but said gasket will sufficiently cover the surface of the shoulder or abutment 13 to insure a steam tight joint when the cap is in place on the bearing sleeve.

15 I do not in this application claim the method of providing a metal packing between two members herein described,—the same being covered in my copending application Serial No. 357,594.

20 Having fully described my invention what I claim as new and desire to secure by Letters Patent, is:—

1. The combination with a hollow member having an internally threaded portion 25 and also an internal annular shoulder adjacent to the inner end of the threaded portion, of a metal gasket lying flatly against said shoulder and having its peripheral portion extending radially past the free edge of 30 the threads of the threaded portion of said

member, whereby said gasket is prevented from escape from said hollow member.

2. The combination with a cap or closure for a staybolt structure, said cap having an internally threaded portion and a shoulder near the inner end of said threaded portion, of a metal gasket lying flatly against said shoulder and extending radially beyond the free edge of the threads of 35 said threaded portion.

3. In a staybolt structure, the combination of a bearing sleeve adapted for connection with a boiler sheet and having an interior rounded seat for the rounded head of a staybolt, a staybolt having a rounded head 40 mounted on said seat, said bearing sleeve having a threaded portion, a threaded closure to engage the threaded portion of the sleeve, one of said parts having an annular abutment for the other part, and a metal 45 gasket on said abutment and extending radially beyond the free edges of the screw threads of the threaded portions.

In testimony whereof, I have signed this specification in the presence of two sub- 50 scribing witnesses.

FREDERICK K. LANDGRAF.
